DEVICE FOR DRAWING OFF LIQUIDS.

1,128,002.

Specification of Letters Patent.

Patented Feb. 9, 1915.

Application filed May 27, 1913. Serial No. 770,173.

To all whom it may concern:

Be it known that I, PAUL KESSELER, engineer, a subject of the German Emperor, and a resident of Berlin-Steglitz, Germany, have invented certain new and useful Improvements in Devices for Drawing Off Liquids, of which the following is a specification.

My invention relates to devices for drawing off liquids, and particularly inflammable liquids such as gasolene, and is particularly applicable to systems in which the pipe for conveying the inflammable liquid to the place of discharge is surrounded by a pipe or jacket containing gas under pressure, said 10 gas being in communication with the body of gas contained in the upper portion of the receptacle holding the inflammable liquid, the latter being driven to the discharge point by the pressure of said gas. 15 The drawing-off device forming the subject-matter of my present invention has for its purpose to prevent the escape of the inflammable liquid in case the device for shutting off the conveying pipe should become 20 inefficient or leaky, without however interfering with the drawing of liquid at any other discharge points that may be connected with the same conveying pipe, as long as the shut-off devices at such points are in 25 a serviceable condition. According to my invention, this result is obtained by interposing, between the conveying pipe and the discharge pipe, an intermediate chamber 30 which may be shut off from each of said 35 pipes by appropriate valves or equivalent devices. When said devices are in the closed position, the intermediate chamber communicates by a channel with the space of the jacket containing gas under pressure. Thus 40 the shut-off device which is nearest the discharge opening is normally exposed to the pressure of said gas, so that if the shut-off device of the conveying pipe should leak, the liquid contained in said pipe will be 45 forced back by the pressure of the gas, but will not be able to escape through the outlet or discharge pipe. When the device for shutting off the discharge pipe is moved to 50 its open position, the first effect of such movement will be to close the channel connecting the intermediate chamber with the gas space of the jacket, and then the shut-off device of the conveying pipe is opened. 55 The inflammable liquid can then pass from the liquid-conveying pipe through its open

shut-off device into the intermediate chamber which at that time is disconnected from the gas space of the jacket, and can then pass into the discharge pipe through the open shut-off device of said pipe. When 60 the drawing of the liquid is discontinued, the shut-off device of the liquid-conveying pipe is closed first, and then the intermediate chamber is placed in communication with the gas space of the jacket, whereupon the 65 shut-off device of the discharge pipe is closed, which shut-off device is nearest the outlet.

A typical example of my invention is shown in the accompanying drawings, in 70 which—

Figure 1 is a vertical section of the improved apparatus, and Fig. 2 is a detail end view of one of the valves or shut-off devices.

The receptacle containing the gasolene or 75 other inflammable liquid is not shown in the drawings, but 1 designates the liquid-conveying pipe which dips into the liquid contained in said receptacle. The drawing shows only the upper end or upper section 80 of said pipe. The pipe 1 is surrounded by a jacket-forming pipe 2, the space between the two pipes communicating with the upper portion or gas space of said receptacle, so that the gas under pressure contained in 85 said receptacle above the liquid, will also fill the pipe 2, around the pipe 1. Of course, the drawing shows only the upper end or upper section of the pipe 2. At the top, the pipe 2 is enlarged to form a casing 3, 90 surrounding, at a distance, the upper portion of the liquid-conveying pipe 1 as well as an intermediate chamber 5 interposed between the pipe 1 and the discharge pipe 4. The interior of the intermediate chamber 5 95 communicates, under normal conditions, with the gas space or jacket of the pipe 2, as by means of a channel 6, preferably located at the upper portion of said chamber. The shut-off device for the liquid-conveying pipe 100 1 is shown as a valve 7 having a stem 8 around which is coiled a spring 9 one end of which bears against the valve and the other against a suitable stationary part, as a portion of the casing 3, said spring tending to seat or close the valve 7. The valve seat is formed by an annular flange 10 provided at one end of the perforated plug 11 which is screwed into the casing 3. The valve 7 has spaced longitudinal ribs 12 in 110

guiding engagement with the inner wall of the plug 11, the spaces 13 between said ribs forming ducts for the passage of gas or liquid. A ring-washer 14 is fitted to the 5 plate of the valve 7 on the side facing the seat.

As a device for shutting off the discharge pipe 4, I have shown a piston valve 15 secured to the inner end of a stem or rod 16, 10 the outer end of which engages the lower arm 17 of the operating handle or lever 19 fulcrumed on the casing 3 at 18. The piston valve 15 is provided with a washer or packing 20 and is adapted to become seated upon an annular flange 21 projecting into the intermediate chamber 5. The inner surface of the piston valve 15 is engaged by one end of a coiled spring 22, the other end of which bears against an annular plate 23 contained 20 in the chamber 5. The piston valve 15 is guided during its longitudinal movement (brought about by operating the lever 19, or by the action of the spring 22), by means of a cylindrical guide portion 24 formed in the 25 chamber 5, the channel 6 being provided at the upper portion of said guide 24, while its lower portion is provided with a duct 25 for the passage of the inflammable liquid from the pipe 1 to the pipe 4, when the valve 30 7 and the piston valve 15 are open.

The inner end of the valve stem or rod 16 is normally out of contact with the neighboring face of the valve 7, so that upon swinging the lever or handle 19 in the direction indicated by the arrow, the piston valve 15 will first be moved independently of the valve 7 so as to close the channel 6 of the valve 7 so as to close the channel 6 and interrupt the communication between the chamber 5 and the jacket 2, 3. Then, 40 the inner end of the stem 16 will engage the valve 7, so that the further movement of the handle 19 will cause the valve 7 to be moved from its seat 10.

In the normal position, or position of rest, 45 shown in Fig. 1, the piston valve 15, which is adjacent to the outlet or discharge pipe 4, is exposed to the pressure of the gas contained in the jacket 2, 3, since said jacket communicates with the chamber 5 through the channel 6. Therefore, should the valve 50 7 leak, the gas under pressure will pass from the chamber 5 through the leaky valve into the liquid-conveying pipe 1 and will drive the liquid in said pipe back into the receptacle.

When drawing off the inflammable liquid by moving the handle 19 in the direction indicated by the arrow, the chamber 5 is first disconnected from the gas space of the 60 jacket by the piston valve 15 covering the orifice of the channel 6, and then the valve 7 is opened to allow the inflammable liquid to pass from the pipe 1 through the ducts 13 into the chamber 5 and from the latter 65 through the duct 25 to the discharge pipe 4.

Various modifications may be made without departing from the nature of my invention as set forth in the appended claims. Thus, other devices performing the same operation may be substituted for the particular valves described above. The temporary connection of the chamber interposed between the liquid-conveying pipe and the discharge pipe, with a space containing gas under pressure, may be effected 75 by means other than those described and shown in this application.

I claim:

1. The combination of a liquid-conveying pipe, a discharge pipe, a chamber interposed between said pipes, a valve controlling the connection of the liquid-conveying pipe with said chamber, another valve controlling the connection of said chamber with the discharge pipe, and a chamber adapted to 80 contain gas under pressure and communicating with a channel leading to the first-named chamber, said channel being open to establish a communication between said two chambers when the valves are closed, but 85 being adapted to be closed so as to interrupt said communication by the opening movement of the valve controlling the outlet pipe, and means for operating said valves.

2. The combination of a liquid-conveying 90 conduit, a discharge conduit, a chamber interposed between said conduits, separate valves controlling the connection of said chamber with the respective conduits, a gas chamber communicating with said chamber 100 when both valves are closed, and operating means arranged to open said valves but to interrupt the connection between the gas chamber and the first-named chamber before opening the valve which controls the connection of the said first-named chamber with the liquid-conveying conduit.

3. The combination of a liquid-conveying conduit, a discharge conduit, a chamber interposed between said conduits, a gas chamber normally communicating with said chamber, a valve controlling the connection of the first-named chamber with the liquid-conveying conduit, another valve controlling the connection of the first-named chamber 110 with the discharge conduit and also the connection with the gas chamber in such a manner as to close one connection when the other is open and vice versa, and means for first operating the last-named valve and 115 then the first-named valve.

4. The combination of a liquid-conveying conduit, a discharge conduit, a chamber interposed between said conduits, a gas chamber normally communicating with the first-named chamber, a valve controlling the connection of the first-named chamber with the liquid-conveying conduit, another valve, having a limited movement relatively to the 125 first-named valve, and controlling the con- 130

nection of the first-named chamber with the discharge conduit and also its connection with the gas chamber in such a manner as to close one connection when the other is open 5 and vice versa, and means for operating the said valves successively.

5. The combination of a liquid-conveying conduit, a discharge conduit, a chamber interposed between said conduits, a gas chamber 10 normally communicating with the first-named chamber, a valve controlling the connection of the first-named chamber with the liquid-conveying conduit, another valve, having a limited movement relatively to the 15 first-named valve, and controlling the connection of the first-named chamber with the discharge conduit and also its connection with the gas chamber, means for operating said valves successively, and separate means 20 tending to return each of said valves to its closed position.

6. The combination of a liquid-conveying conduit, a discharge conduit, a chamber interposed between said conduits, a gas chamber

ber normally communicating with the first- 25 named chamber, valves controlling the connection of the first-named chamber with the liquid-conveying conduit and with the discharge conduit respectively, and means for operating said valves. 30

7. The combination of a liquid-conveying conduit, a discharge conduit, a chamber interposed between said conduits, a gas chamber normally communicating with the first-named chamber, valves having a limited 35 movement relatively to each other and controlling the connection of the first-named chamber with the liquid-conveying conduit and with the discharge conduit respectively, and means for operating said valves suc- 40

In testimony whereof I have signed this specification in the presence of two subscribing witnesses.

PAUL KESSELER.
